Primary Examiner — Messina L Smith*Assistant Examiner* — Kwabena A. Ankobiah(57) **CLAIM**

The ornamental design for a tablet computer as shown and described.

DESCRIPTION

The file of this patent contains at least one drawing executed in color. Copies of this patent with color drawings will be provided by the Office upon request and payment of the necessary fee.

1. Tablet computer
- 1.1 : Front
- 1.2 : Back
- 1.3 : Top
- 1.4 : Bottom
- 1.5 : Right
- 1.6 : Left
- 1.7 : Perspective

The broken lines in the reproductions illustrate portions of the tablet computer that form no part of the claimed design. Portable condition monitoring system to handle the tasks required to perform predictive maintenance on rotating
